UNITED STATES PATENT OFFICE

PERCY L. HILL, OF NEW YORK, N. Y.; JAMES W. ANDERSON ADMINISTRATOR OF SAID
PERCY L. HILL, DECEASED

CHARACTER CARRIER FOR COMPOSING MACHINES

Application filed August 12, 1919. Serial No. 317,044.

This invention relates to composing machines, such as the linotype, the intertype, and other machines, where the character carrying elements are provided with indicating 5 characters for the guidance of the operator, etc., and with respect to its most specific features to the character carrying element of such machines, as for instance exemplified in that of the linotype machine and others 10 involving line casting operations.

One of the objects of the invention is the provision of a practical character carrying element by means of which eye-strain in reading one or more characters is practically 15 eliminated.

Another object of the invention is the provision of an efficient character carrying element wherewith the operation of composing may be effected with a high degree of 20 accuracy.

Another object of the invention is the provision of a character carrying element the utilization of which results in an increased output of work.

Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawing forming 35 part of this specification, and wherein similar reference characters refer to similar parts throughout the several views.

Fig. 1 is a perspective view of a character carrying element embodying the invention;

Fig. 2 is a side view of Fig. 1, showing the opposite side, and,

Fig. 3 is a sectional detail of a portion of the character carrying element.

For the purpose of disclosing the invention, there is illustrated a character carrying element, or carrier, 1, such as is ordinarily employed in a linotype machine. This element is provided with the usual appurtenances which co-operate in the machine 50 to select and deliver it to the type casting

operation and to distribute it after casting. It is to be understood, however, that the invention is adapted for other types of composing machine and for character carrying elements of different kinds.

The numeral 2 indicates one edge of the carrier, 1, on which is a "character" such as a letter, numeral, or other sign to be reproduced in the composition. On the opposite edge of the carrier is another "character", indicated by the numeral 3, being, in the present instance, the letter "H", which indicates to the operator that the character on the opposite edge is also the letter "H". The foundation of the carrier, 1, may be of brass or other metal, and the indicating character, 3, is impressed therein as by being sunk, or made "intaglio", in its edge.

The indicating character, 3, is made to contrast sharply in color with the surrounding surface, or field 4, the indicating character being white and the surrounding surface, or field dark as, black, the white character being clearly and distinctly visible upon the black field.

To obtain such result in the character carrying element illustrated, the intaglio indicating character 3 and the surface 4, in which it lies may be treated to color both black, as for instance by treating it with suitable chemicals which will color the brass black.

Then the intaglio indicating character may be given the sharply contrasting color by a light colored, or white filling. For example, 85 by employing a white paint of proper consistency, the intaglio indicating character may be filled in flush with the surface in which it lies, as illustrated in Fig. 3 which shows a section of a portion of the carrier 1 90 transversely of the cross line 5 in the letter "H".

The coloring for the field and for the indicating character should be as permanent as possible and the filling for the indicating 95 character should be such as to be firmly retained in place. It will be understood that in line casting machines, the character carrying element or matrix must come in contact with molten type metal and therefore, 100

that the coloring substances selected should be those which are not injuriously affected by such heat.

In this wise not only is the indicating character 3 in sharp color contrast to that of the surrounding surface in which it lies, but, as well, the light-reflecting quality of the field as compared with that of the indicating character conduces to the more ready reading of the indicating character. The dark, as black, field of the carrier, is of subdued or low light-reflecting quality so that rays from this source do not impair the clear view of the indicating character, as for instance, by dazzling the sight. On the other hand, the white indicating character, while of high light-reflecting quality, is relatively small in area as compared with the dark field, and stands out in the dark field as a relatively bright character, the shape of which is immediately appreciated by the eye of the observer.

The operators of composing machines of the kind referred to work under conditions which not only render it difficult to read the indicating characters of the carriers but cause severe eye-strain, due to the constant attention required in reading for long periods of time under poor lighting conditions, most of the work being done under electric light. This light is ordinarily directed upon the exposed edges of the line of carriers or matrices when collected in the assembly box and since these edges have heretofore been usually of brass, have high light reflecting quality, an injurious glare of light has been reflected into the eyes of the operators. The usual indicating character of a composing machine is merely a properly shaped recess in the edge of the carrier, the recess being of the same color as the surrounding surface. Eye-strain consequent upon the reading of such indicating characters is evident. By applicant's invention such eye-strain is practically eliminated, even under the poor lighting conditions usually found. In consequence of this relief, the accuracy of the work is enhanced, the eye being able to function more correctly because of relief from strain. As a further consequence, the output of work is increased because of the fact that the line of character carrying elements in course of assembly may be easily read and any errors quickly perceived and corrected. When it is remembered that the positioning of an improper character in a single line in a linotype machine requires the recasting of the entire line, the increased efficiency by reason of the elimination of tendency to error in this regard is apparent.

Thus, by the above described construction, are accomplished, among others, the objects hereinbefore referred to.

As many changes could be made in the above construction and many apparently

widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A character carrying element for composing machines having on its edge an indicating character in white on a black field.

2. An element of the kind described made of metal and having on one edge a character to be reproduced in the operation of the machine, and on the other edge a character indicative of the character on the first mentioned edge, the edge surface surrounding the character on the second mentioned edge being treated to make it dark, the second mentioned character being white.

3. A character carrying element for line casting machines having on its edge an indicating character in sharp color contrast to that of the surrounding surface of said element.

4. A character carrying element for line casting machines having on its edge an indicating character in sharp color contrast to that of the surrounding surface of said element and of higher light-reflecting quality than that of the surrounding surface of said element.

5. A character carrying element for line casting machines having on its edge an indicating character in sharp color contrast to that of the surrounding surface of said element and of higher light-reflecting quality than that of the surrounding surface of said element, the light-reflecting quality of said surrounding surface being low and that of said character being high.

6. A metal character carrying element for line casting machines, having on its edge an indicating character and having the metal of said element surrounding said indicating character treated to provide a surface of subdued light-reflecting quality as compared with the light-reflecting quality of said indicating character.

In testimony whereof I affix my signature.

PERCY L. HILL.
